UNITED STATES PATENT OFFICE.

CHARLÉ C. WILLIAMS, OF CLEVELAND, OHIO.

CLAM-SHELL BUCKET.

No. 878,585.

Specification of Letters Patent.

Patented Feb. 11, 1908.

Application filed May 10, 1907. Serial No. 372,876.

To all whom it may concern:

Be it known that I, CHARLÉ C. WILLIAMS, a citizen of the United States, resident of Cleveland, county of Cuyahoga, and State of Ohio, have invented a new and useful Improvement in Clam-Shell Buckets, of which the following is a specification, the principle of the invention being herein explained, and the best mode in which I have contemplated applying that principle, so as to distinguish it from other inventions.

My invention relates to improvements in ore buckets, particularly ore buckets of the clam-shell type.

15 In using the term "ore bucket" it should be prefaced that, of course, such bucket is adapted for handling other materials as well as ore; the field indicated, however, presents one of its larger fields of usefulness.

20 The object of said invention is to provide a bucket of the type indicated that will be economical in construction and also in the power required to operate the same, being operable by means of a single rope or cable, 25 a further object being the provision of means whereby such bucket's operation shall be more or less automatic in character.

To the accomplishment of these and related ends said invention consists of means 30 hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings: Figure 1 represents in end elevation a bucket embodying my improved principles of construction, such bucket being represented in its closed position; Fig. 2 is a side elevation of such bucket in the same closed condition as shown in Fig. 1; Fig. 3 is a side elevation of such bucket in 45 its open condition; Figs. 4 and 5 are, respectively, a side elevation and an end elevation of an automatic release designed to be incorporated when desired in the structure illustrated in the preceding figures; and Fig. 50 6 is a broken longitudinal section taken through the scoops in their open position.

Having reference, first of all, to Figs. 1, 2, and 3, particularly, the relatively fixed portion of my improved bucket will be seen to 55 comprise a frame A. This frame consists primarily of four side-plates a a in which are

transversely mounted three shafts a', a² and a³, whereby such side-members are kept properly spaced and a rigid frame structure at the same time provided. These shafts have an additional function, as will be presently set forth. The bucket proper comprises two scoop members B B, the form of which may be varied to suit the character of the service in which the bucket is designed 60 to be employed. Such scoop-members are pivotally connected at their inner ends by means of two bifurcated arms B' B², preferably of cast-metal construction, the lower ends of which are strongly riveted to the 65 inner portions of the upper edges of the scoop-members, the arms themselves being secured together by means of a pintle shaft b to form a hinge. The outer ends of the scoop-members B are supported from frame 70 A by means of similar pairs of links b' b', as shown, which links are pivotally attached at their upper ends to the centrally-disposed shaft a' of the three shafts referred to as being mounted in such frame A, the lower 75 ends of which are pivotally attached to clips b² riveted to the rear or closed ends of the scoop-members B. Riveted to the upper portion of each of the two at one end of the bucket are plates a⁷ in which the ends of 80 shaft a², projecting through outermost plates a, are journaled. The object of these plates a⁷, is to prevent the rotation of frame A about central shaft a', such as might otherwise occur. Of such two arms B' B² the 85 one B² is considerably longer than the other, and by virtue of their pivotal connection they are obviously adapted to permit oscillation of the respective scoop-members B about their points of attachment to links b' 90 to open or close, as may be desired.

In the longer arm B², about midway of pivotal shaft b, and the arm's outer or free end, is mounted a second shaft b⁴, parallel with such shaft b, that bears a trip member B³. The lower portion of such trip member terminates in a foot b⁵, the upper portion of such member being provided in effect by a latch b¹¹ that is likewise mounted on shaft b⁴ and is adapted to engage with a lug b¹⁰ on the 95 inner face of one of the bifurcated ends of scoop-arm B'. The disposition of trip member B³ and such lug b¹⁰ is such as to permit the aforesaid engagement to take place only when scoop-members B are fully extended 100 or opened, Figs. 3 and 6. When trip member B³ is thus in engagement with lug b¹⁰,

the scoop-members are effectually locked against closing, as will be evident. In this locking position of the trip member, its outer foot portion b^5 lies below a plane passing through the lowermost portions of the open scoop-members, as is shown in Fig. 3, above referred to. Mounted in the outer or free end of the longer scoop-arm B^2 upon a shaft b^3 parallel with the pivotal axis b of such 10 arm, and hence with trip-arm-shaft b^4 as well, are two pulleys or sheaves b^6 b^6 . Such sheaves are partially incased in a protective housing b^7 , preferably formed integral with the terminal portion of the arm, the object 15 of such housing being to prevent the entrance of the material being handled into the bearings of the sheaves, or between the sheaves and the cable hereinafter described as running around the same, when arm B^2 is 20 horizontally disposed in the open position of the scoop-members, Fig. 3. Just below the axis b^3 of sheaves b^6 , in the outer portion of arm B^2 , is another transversely-disposed shaft b^8 , from which is hung a transversely- 25 disposed sheave b^9 , the casing of which is free to oscillate, as will be evident, about such shaft b^8 as an axis. Mounted upon shaft a^3 , which has already been described as 30 transversely-disposed in one end of the frame structure A , which I shall here for convenience of future reference term the front end, is a pair of pulleys a^5 disposed in proper alignment with pulley b^6 in the outer end of scoop-arm B^2 . Upon the shaft a^3 in the opposite, or rear, end of frame structure A is 35 mounted a second pair of smaller guide-pulleys or sheaves a^6 .

As has been indicated, the operation of my bucket is designed to be effected by means of 40 a single rope or cable, this cable being designated by reference letter C in the several figures of the drawings. Cable C has its ends variously connected exteriorly of the bucket depending on the manner in which it is found 45 preferable to operate the latter. In the first and more generally adaptable method of use it will be assumed that one such end is fixedly secured exteriorly of the mechanism constituting the ore bucket structure, as to the 50 end of a derrick-boom, bridge traveler, or the like, depending on the character of the unloading plant. The other or free end of such cable is then designed to pass over a pulley in such derrick end in the usual fashion 55 (and hence not illustrated), to the drum of the hoisting mechanism, whereby it may be drawn in or paid out as desired, and with results as hereinafter indicated in the operation of the bucket. Such dead-end 60 cable is looped around transversely-disposed sheave b^9 in the outer portion of scoop-arm B^2 , and the free and dead-end portions, respectively, of the same, thence passed from such loop over one of the sheaves a^5 in frame 65 A and one of the parallel-disposed sheaves

b^6 , in the extreme outer end of such scoop-arm B^2 , in the order named. Both the free and dead-end portions are guided upwardly as they leave sheaves b^6 by being passed behind the aforesaid guide-sheaves a^6 in the 70 rear end of frame A . The single cable C , by virtue of its external attachment and its disposition just described about the several sheaves mounted in scoop-arm B^2 , is obviously adapted, upon its free end being 75 drawn in, to close scoop-members B , and when said members are thus closed, to support and raise the bucket structure in its entirety.

In addition to the bucket-supporting 80 means thus provided by operating cable C , I utilize exterior supporting means D comprising essentially a base member or cross-head d from which depend two side-plates d' . Between the latter is pivotally hung on 85 a transverse axis d^4 a hook d^2 that is formed with a rearwardly extending heel, to which is conveniently attached release cable D' . The lower ends of side-plates d' are bifurcated, Figs. 2 and 3, and are adapted, when 90 hook d^2 hangs in its normal pendent position, to inclose therewith a vertical oblong space, the width of which is sufficient to accommodate readily transverse shaft a' of frame structure A , from which are supported, as 95 has been described, scoop-members B of the bucket. Engagement of such shaft a' of frame A with hook d^2 is effected upon such shaft being raised against the lower curved face of the hook as it lies between the bifurcated ends of side-plates d' , the effect of the pressure of the shaft against the hook being 100 to swing the latter rearwardly until the shaft has been raised above its lip. Thereupon the hook swings again into place, and 105 upon now lowering the bucket, *i. e.* frame A and shaft a' , such shaft, and thereby the rest of the bucket structure, will be held and sustained by the hook. The length of the oblong space formed between the upper face 110 of the hook and the bifurcation in the respective side-plates d' , is designed to be just sufficient to permit the movement of shaft a' described. Swinging of hook d^2 in a forward direction is prevented by means of a pin d^3 extending between plates d' ; this pin, 115 at the same time, serves to hold the plates properly spaced. The transverse base member or cross-head from which hook d^2 is pivotally hung is suspended by means of a cable d^2 or the like from the same derrick-boom, traveler, or equivalent structure, in which is secured the dead-end of operating cable C , as also the pulley over which passes the free 120 end of the last-named cable. In other words, the dead-end and free end portions of cable C , along with cable D' , lie parallel as shown, and, in order to prevent undue swaying of the operating cable portions, as also to prevent their chance disengagement from 125 130

the sheaves of the bucket structure, they are preferably passed through suitable apertures therefor provided in the lateral portions of the aforesaid cross-head d . This effect may be still further enhanced by the provision of a tube d^5 rigid with the portion of such cross-head through which passes the dead-end portion of cable C, such tube being of greater or less length, as found best in actual service, by means of which it will be obvious an increased steadyng effect is obtained without any objectionable wearing features, since the dead-end portion of cable C does not move relatively to the cross-head in the ordinary operation of the device.

Supporting means D, in the form that has just been described, constitute what I term a "semi-automatic releasing device." In Figs. 4 and 5 I illustrate releasing means adapted to be incorporated in the structure of bucket frame A and designed to operate in conjunction with such semi-automatic means to render their action wholly automatic. Before taking up, however, the description of the latter, it is deemed advisable to describe the operation of the bucket, since such operation is concerned in the operation of the automatic releasing mechanism, and its understanding will facilitate a comprehension of the latter.

As shown in Figs. 1 and 2, the scoop-members of the bucket appear in their closed position which they occupy only when filled. In other words, the stage of the operation there shown is that just subsequent to the closing of the scoop-members on the pile, which, as will be remembered, is effected by drawing in the free end portion of joint operating and supporting cable C. In said Figs. 1 and 2, such cable C is represented in the performance of its second or supporting function only. By means of it, then, the bucket is raised until shaft a' of frame A is engaged and held by the hook d^2 of exterior supporting means D. The weight, however, of the closed and loaded bucket is sustained by cable C, or, in other words, the free end portion of such cable is not paid out at all until the derrick-boom or equivalent structure has been operated to swing or move the bucket into the position where it is desired to dump the same. Only then is cable C paid out. It will be understood of course that in practice the swinging or other movement of the bucket is usually effected simultaneously with the elevation of the latter so that no time is lost in simply raising the bucket after it has been closed. The weight of the bucket structure is now supported, as will be evident, by the hook d^2 , and the paying out of cable C permits the automatic depression of scoop-arm B^2 and the opening of the scoop-members, the final dumping position being shown in Fig. 3. Incidentally to the assumption by the scoop-members of their

open position, trip member B^3 engages lug b^{10} and locks the scoop-members against closure, as has been described. The bucket being dumped, is now swung or moved back until it again hangs over the pile. To lower it into the latter, cable C is drawn in slightly, just enough to raise shaft a' of frame A out of contact with hook d^2 , which latter can thereupon be withdrawn by a jerk on releasing cable D' . The open bucket is now lowered onto the pile by means of operating cable C, which however, is prevented from closing the bucket, as will be understood, by the locking action of trip B^3 . Such locking action continues until the foot of the trip comes in contact with the pile, pressure from beneath upon such foot being adapted, in the manner previously explained, to effect the oscillation of the trip sufficient to release it from lug b^{10} . Consequently, upon cable C being now again drawn in, its first action will be to close the scoop-members, and only to raise them after such closure has been effected, this being the stage of operation with which the description began.

To obviate the necessity of jerking, by means of releasing cable D' , hook d^2 out of engagement with shaft a' of frame A, preliminarily to lowering the open bucket onto the pile, I have devised the automatic release which I shall now describe. This device comprises a reciprocable arm E centrally disposed in frame structure A, Figs. 4 and 5, the front end of which is provided with an elongated opening e^7 adapted to fit over shaft a^2 , whereby its reciprocation is limited. Such reciprocable member E is further supported by means of two inwardly-curved arms e^8 pivotally hung from shaft a' , and pivotally connected to such member E by a pin e^9 . Arms e^8 extend a short distance below this point of pivotal attachment to member E, and have secured between them a block or cross-head e^2 through which is slidably fitted the lower end of a rod e^3 whose upper end is secured in a lug e^4 on the underside of member E. A helical expansion spring e^5 , or equivalent resilient member, is fitted over rod e^3 between lug e^4 and cross-head e^2 . The tendency of spring e^5 will obviously be to urge member E rearwardly into its lowermost position, that shown in dotted outline, Fig. 4. The lower end of the member is given a crescent or like concave formation, and is of such a length as to be engaged by the shaft in the outer end of scoop-arm B^2 , whereon sheaves b^6 are mounted, in the closed position of the bucket. By such engagement member E is maintained in its forward or upper position, spring e^5 being correspondingly compressed. The upper portion of member E is provided with an upstanding lug e^6 , that is adapted in the inoperative position just described as being effected by the closure of the bucket, to rest

against the lip of hook d^2 when shaft a' is engaged and held by said hook. When shaft a' is thus held and the weight of the bucket structure supported therefrom, it will be evident that the action of spring e^5 will be ineffective to dislodge the hook, in spite of the removal of shaft b^3 out of engagement with the lower end of said member E . However, upon the bucket-structure, including shaft a' , being slightly raised as before, the weight only of the hook now being opposed to the action of spring e^5 , the latter will promptly force member E rearwardly and thus swing such hook clear of shaft a' and permit the bucket to be lowered. This action, it will be seen, is wholly automatic and does away with the necessity of jerking on release cable D' , so that the latter may be entirely dispensed with. Whether this last described automatic release be employed or not, it will be obvious that my improved type of bucket in itself is characterized by various structural and operative features that commend it for use generally in loading and unloading plants. It will of course be understood that, as has been stated before, such bucket may be hung and operated from a traveler or carriage, in a "bridge" unloading plant just as successfully as from a boom where a derrick is employed. By dead-ending the operating cable upon the boom or bridge, a double turn or more of the cable may be easily had between the bucket frame and the scoop-arm, and the closing of the bucket effected with a corresponding lower expenditure of power; while by utilizing the same operating cable to support and raise the bucket, when closed, and to lower the same after being dumped, the operation of the bucket is much simplified without any increase in complexity in the bucket structure.

It has been previously intimated that other methods of exteriorly connecting the two ends of cable C , than the one above assumed, might be advantageously employed. Thus, where sufficient power is to be had, both ends may be attached to the hoisting drum and simultaneously paid out or drawn in. Sheave b^9 thereupon becomes in effect an equalizer sheave, the two portions of the cable acting substantially independently. This method of connecting up the cable will be frequently found desirable where it is sought to install my improved bucket in existing plants; such attachment will be practically accomplished by simply securing the ends in question to a cross-bar into which the regular hoist block can be directly hooked, as will be readily apparent. Hook d^2 , where this arrangement maintains, is then preferably connected with a pole and manually swung into place to engage the bucket shell, and similarly withdrawn, as at present.

Other modes of applying the principle of

my invention may be employed instead of the one explained, change being made as regards the mechanism herein disclosed, provided the means stated by any one of the following claims or the equivalent of such stated means be employed.

I therefore particularly point out and distinctly claim as my invention:—

1. In mechanism of the class described, the combination of a frame; two scoop members pivotally connected at their inner ends; links connecting the outer ends of said members with said frame; and a cable having one end secured exteriorly of said mechanism and connected to support said frame and members and normally close the latter.

2. In mechanism of the class described, the combination of a frame; two scoop members; arms borne by the inner portions of said members, respectively, said arms being pivotally secured together; links connecting the outer ends of said members with said frame; sheaves in the outer end of one of said arms and in said frame; and a cable having one end fixedly secured exteriorly of said mechanism and passing around said sheaves, said cable being adapted to support said frame and members and to normally close the latter.

3. In mechanism of the class described, the combination of a frame; two scoop members pivotally connected at their inner ends, one of said members bearing an arm; links connecting the outer ends of said scoop members with said frame; three sheaves mounted in the free end of said scoop arm; two sheaves mounted in said frame; and a cable looped around one of the sheaves in said arm, the respective portions of said cable passing over one of the sheaves in said frame and one of the remaining sheaves of said arm in the order named.

4. In mechanism of the class described, the combination of a frame; two scoop members pivotally connected at their inner ends, one of said members bearing an arm; links connecting the outer ends of said scoop members with said frame; a pair of vertically disposed and one transversely disposed sheave mounted in the outer end of said scoop arm; a pair of vertically disposed sheaves mounted in said frame; and a cable looped around the transversely disposed sheave in said arm; the respective portions of said cable passing over one of the sheaves in said frame and one of the pair of vertical sheaves in said arm in the order named.

5. In mechanism of the class described, the combination of a frame; two scoop members pivotally connected at their inner ends; one of said members bearing an arm; links connecting the outer ends of said scoop members with said frame; three sheaves mounted in the outer end of said scoop arm; two sheaves mounted in said frame; and a dead

end cable looped around one of the sheaves in said arm, the free and dead-end portions, respectively, of said cable passing from such loop over one of the sheaves in said frame and one of the remaining sheaves of said arm in the order named.

6. In mechanism of the class described, the combination of a frame; two scoop members pivotally connected at their inner ends, 10 one of said members bearing an arm; links connecting the outer ends of said scoop members with said frame; a pair of vertically disposed and one transversely disposed sheave mounted in the outer end of said scoop arm; 15 a pair of vertically disposed sheaves mounted in said frame; and a cable looped around the transversely disposed sheave in said arm, one end of said cable being fixedly secured exteriorly of the mechanism, and the free 20 and dead end portions, respectively of said cable passing from such loop over one of the sheaves in said frame and one of the remaining sheaves of said arm in the order named.

7. In mechanism of the class described, 25 the combination of a frame, two scoop members pivotally connected at their inner ends, one of said members bearing an arm; links connecting the outer ends of said scoop members with said frame; three sheaves mounted 30 in the outer end of said scoop arm; two sheaves mounted in said frame; a cable looped around one of the sheaves in said arm, the respective portions of said cable passing from such loop over one of the sheaves in 35 said frame and one of the remaining sheaves in the arm in the order named; and guide sheaves in said frame adapted to receive and guide such cable portions upwardly from such remaining arm sheaves.

- 40 8. In mechanism of the class described, the combination of a frame; two scoop members; arms borne by the inner portions of said members, respectively, said arms being pivoted together; links connecting the outer 45 ends of said scoop members with said frame; a pair of sheaves vertically mounted in the outer end of one of said arms; a third transversely disposed sheave mounted in such arm end and oscillatory about an axis at 50 right angles to its own axis; a pair of sheaves vertically mounted in said frame; a cable looped around said transversely disposed sheave in such arm end, one end of said cable being fixedly secured exteriorly of the mechanism, and the free and dead end portions, 55 respectively, of said cable passing from such loop over one of the sheaves in said frame and one of the vertical sheaves in said arm in the order named; and guide sheaves in 60 said frame adapted to receive and guide such cable portions upwardly from such vertical arm sheaves.

9. In mechanism of the class described, 65 the combination of a frame comprising side plates; a shaft mounted therein intermediately

of said frame's ends; two scoop members; arms borne by the inner portions of said scoop members, respectively, one of said arms being longer than the other and the one being pivoted to the other; links having 70 their upper ends mounted on the end of said frame shaft and their lower ends pivotally attached to the outer portions of said scoop members; a pair of sheaves vertically mounted in the outer portion of said longer scoop arm; a third transversely disposed sheave mounted in said arm end and oscillatory about an axis at right angles to its own axis; a pair of sheaves vertically mounted in one end of 75 said frame; a cable looped around said transversely disposed sheave in such arm end, one end of said cable being fixedly secured exteriorly of the mechanism, and the free and dead end portions, respectively, of said cable passing from such loop over one of the 80 sheaves in said frame and one of the vertical sheaves in said arm in the order named; and guide sheaves mounted in the other end of said frame adapted to receive and guide such cable portions upwardly from such vertical 85 arm sheaves.

10. In mechanism of the class described, the combination of a frame; scoop members supported therefrom and adapted normally to close; and means adapted to lock said 90 members in their open position, such means being operable by pressure from beneath to release said members.

11. In mechanism of the class described, the combination of a frame; two scoop 100 members pivotally connected at their inner ends; links connecting the outer ends of said members with said frame; a cable connected with said frame and members to support the same and normally to close the latter; and 105 means adapted to lock said members in their open position, such means being operable by pressure from beneath to release said members.

12. In mechanism of the class described, 110 the combination of a frame; two scoop members; arms borne by the inner portions of said members, respectively, said arms being pivotally secured together; links connecting the outer ends of said members with 115 said frame; sheaves in the outer end of one of said arms and in said frame; a cable passing around said sheaves and adapted to support said mechanism and normally to close said scoop members; and a trip member 120 pivotally mounted in one of said scoop arms and adapted to lock said arms in the open position of said members, the free end of said trip member lying below the plane of the bottoms of said members when the 125 latter are open and being operable by pressure from beneath to unlock said arms.

13. In mechanism of the class described, 130 the combination of a frame; two scoop members; arms borne by the inner portions

of said members, respectively, said arms being pivoted together; links connecting the outer ends of said scoop members with said frame; a pair of sheaves vertically mounted in the outer end of one of said arms; a third transversely disposed sheave mounted in such arm end and oscillatory about an axis at right angles to its own axis; a pair of sheaves vertically mounted in said frame; a cable looped around said transversely disposed sheave in such arm end, one end of said cable being fixedly secured exteriorly of the mechanism, and the free and dead end portions, respectively, of said cable passing from such loop over one of the sheaves in said frame and one of the vertical sheaves in said arm in the order named; guide sheaves in said frame adapted to receive and guide such cable portions upwardly from such 20 vertical arm sheaves; and a trip member pivotally mounted in said longer scoop arm and adapted in the open position of said scoop members to lock with the other of said arms, the free end of said trip member lying 25 below the plane of the bottoms of said members when the latter are open and being operable by pressure from beneath to unlock said arms.

14. The combination with exterior supporting means; of a frame adapted when raised to engage with and be held by said supporting means; scoop members supported from said frame; and a cable connected to support said frame and members, and when thus supporting the same to tend to close the latter, said members tending to open when supported from said exterior supporting means.

15. The combination with exterior supporting means; of a frame adapted when raised to engage with and be held by said supporting means; two scoop members pivotally connected at their inner ends; links connecting the outer ends of said members with said frame; and a cable having one end exteriorly fixedly secured and looped about said frame and members to support the same independently of said supporting means, said cable tending to close said members when thus supported therefrom, and said members tending to open when supported from said exterior supporting means.

16. The combination with exterior supporting means comprising side plates having their lower ends bifurcated, and a hook pivotally mounted between said side plates; of a frame adapted upon being raised to be engaged between said hook and bifurcated side plates; and scoop members supported from said frame.

17. The combination of exterior supporting means comprising side plates having their lower ends bifurcated, and a hook pivotally mounted between said side plates; of

a frame adapted upon being raised to be engaged between said hook and bifurcated side plates; scoop members supported from said frame; and a cable connected to support said frame and scoop members and when thus supporting the same to tend to close the latter, said members tending to open when said frame is supported from said hook. 70

18. The combination with exterior supporting means; of a frame adapted when raised to engage with and be held by said supporting means; scoop members supported from said frame; a cable connected to support said frame and members, and when thus supporting the same to tend to close the latter, said members tending to open when said frame is supported from said exterior supporting means; and means adapted to release said frame from the latter. 80

19. The combination with exterior supporting means; of a frame adapted when raised to engage with and be held by said supporting means; scoop members supported from said frame; a cable connected to support said frame and members, and when thus supporting the same to tend to close the latter, said members tending to open when said frame is supported from said exterior supporting means; and means adapted automatically to release said frame from the latter. 90

20. The combination with exterior supporting means; of a frame adapted when raised to engage with and to be held by said supporting means; scoop members supported from said frame; a cable connected to support said frame and members, and when thus supporting the same to tend to close the latter, said members tending to open when said frame is supported from said exterior supporting means, and means adapted automatically to release said frame from the latter. 100

21. The combination with exterior supporting means comprising side plates having their lower ends bifurcated, and a hook pivotally mounted between said side plates; of a frame including a transverse shaft, such shaft being adapted upon upward movement of said frame to be engaged between said hook and bifurcated side plates; scoop members supported from said frame; a cable connected to support said frame and scoop members and when thus supporting the same to close the latter, said members tending to open when said frame is supported from said exterior supporting means; and means adapted automatically to release said frame from the latter when said members are open. 105

22. The combination with exterior supporting means comprising side plates having their lower ends bifurcated, and a hook pivotally mounted between said side plates; of a frame including a transverse shaft, such shaft being adapted upon upward movement of said frame to be engaged between said

- hook and bifurcated side plates; scoop members supported from said frame; a cable connected to support said frame and scoop members and when thus supporting the same to close the latter, said members tending to open when said frame is supported from said hook; and means adapted automatically to swing said hook out of engagement with said frame shaft when said scoop members are open.
23. The combination with exterior supporting means comprising side plates having their lower ends bifurcated, and a hook pivotally mounted between said side plates; of a frame including a transverse shaft, such shaft being adapted upon upward movement of said frame to be engaged between said hook and bifurcated side plates; scoop members supported from said frame; a cable connected to support said frame and scoop members and when thus supporting the same to close the latter, said members tending to open when said frame is supported from said hook; and spring actuated means mounted in said frame and tending to swing said hook out of engagement with said frame shaft, the operation of said means being dependent upon the opening of said scoop members.
24. The combination with exterior supporting means comprising side plates having their lower ends bifurcated, and a hook pivotally mounted between said side plates; of a frame including a transverse shaft, such shaft being adapted upon upward movement of said frame to be engaged between said hook and bifurcated side plates; scoop members supported from said frame; a cable connected to support said frame and scoop members and when thus supporting the same to close the latter, said members tending to open when said frame is supported from said hook; and spring actuated means mounted in said frame and tending to swing said hook out of engagement with said frame shaft, the operation of said means being dependent upon the opening of said scoop members and the raising of said shaft out of contact with said hook.
25. The combination with exterior supporting means comprising side plates having their lower ends bifurcated, and a hook pivotally mounted between said plates, of a frame including a transverse shaft, such shaft being adapted upon upward movement of said frame to be engaged between
- said hook and bifurcated side plates; two scoop members; arms borne by the inner portions of said scoop members, such arms being pivotally secured together and the one being longer than the other; links connecting the outer ends of said scoops with said frame; sheaves mounted in the outer end of said longer arm and in said frame; a cable having one end exteriorly fixedly secured and passing around said sheaves, said cable being adapted to support said frame and scoop members and to normally close the latter; a member reciprocably mounted in said frame and adapted to engage said hook when said frame shaft is in engagement therewith; and a spring adapted to actuate said reciprocable member to swing said hook out of such engagement, said longer scoop arm being adapted when in its closed position to hold said reciprocable member against operation.
26. The combination with exterior supporting means comprising side plates having their lower ends bifurcated, and a hook pivotally mounted between said plates; of a frame including a transverse shaft, such shaft being adapted upon upward movement of said frame to be engaged between said hook and bifurcated side plates; two scoop members; arms borne by the inner portions of said scoop members, such arms being pivotally secured together and the one being longer than the other; links connecting the outer ends of said scoop members with said frame; sheaves mounted in the outer end of said longer arm and in said frame; a cable having one end exteriorly fixedly secured and passing around said sheaves, said cable being adapted to support said frame and scoop members and to normally close the latter; a member reciprocably mounted in said frame and adapted to engage said hook when said frame shaft is in engagement therewith; and a spring adapted to actuate said reciprocable member to swing said hook out of such engagement, said longer scoop arm being adapted when in its closed position to hold said reciprocable member against operation and said spring being effective only when said shaft is raised out of contact with said hook.

Signed by me this 6th day of May, 1907.
